UNITED STATES PATENT OFFICE.

ARNOLD L. COUTY, OF MARSHFIELD, OREGON.

THROTTLE GOVERNOR.

Application filed February 25, 1925. Serial No. 11,466.

To all whom it may concern:

Be it known that I, ARNOLD L. COUTY, a citizen of the United States, residing at Marshfield, in the county of Coos and State 5 of Oregon, have invented certain new and useful Improvements in a Throttle Governor, of which the following is a specification.

The present invention relates to a gover- 10 nor for the throttle or butterfly valve of an internal combustion engine and aims to provide a device which will automatically close the butterfly valve regardless of the position of the accelerator.

15 The device is designed particularly for use upon trucks so as to prevent the chauffeurs from driving the truck above a pre-determined speed. The device is so constructed that if the accelerator, either foot 20 or hand controlled, is moved to the full open position, this device will operate so as to tend to maintain the engine at a predetermined even rate of speed.

Another important object of the invention 25 is to provide a governor of this nature which is adapted to be interposed between the accelerator mechanism and the crank of the butterfly valve in place of the usual link structure.

30 Another very important object of the invention is to provide a device of this nature having a very simple structure which will be both efficient and reliable in operation, inexpensive to manufacture and install, durable, 35 not liable to readily get out of order, easy to adjust, and otherwise well adapted to the purpose for which it is designed.

With the foregoing and numerous other 40 objects in view as will appear as the description proceeds, the invention resides in certain novel features of construction, and in the combination and arrangement of parts as will be hereinafter more fully described and claimed.

45 In the drawing—

Figure 1 is an elevation of the device showing the same associated with an accelerator mechanism and the crank of a butterfly valve.

50 Fig. 2 is a longitudinal section through the device.

Referring to the drawing in detail, it will be seen A designates the ordinary intake manifold of an internal combustion engine having the valve B therein controlled 55 by crank C. A bell crank lever D is rock-

ably mounted as at E and is adapted to be operated by an accelerator pedal F or any other suitable conventional means.

A spring G is attached to the lever D so. 60 as to normally hold the accelerator pedal F in a raised position. In place of the link which usually connects the crank C with lever D, my improved device is used.

Referring now particularly to my im- 65 provement, it will be seen that 5 designates a cylinder having the restricted open end 6 and the other end thereof closed by a plate 7 held in place by screws 8 or other suitable means. This plate 7 is provided with an 70 opening 9 thru which is slidable a rod 10 the end of which is offset as at 11 in order to be passed through the eye of crank C held in place by a cotter pin 12 or the like.

A plunger member 13 is affixed to this rod 75 10 within the cylinder. A tubular member 14 is threaded through the opening of the end 6 of the cylinder 5 and is closed at its outer end and open at its inner end. A spring 15 is disposed about the rod 10 and 80 impinges against the plunger member 13 and the closed end of the tube 14, for normally holding the plunger 13 adjacent the plate 7. A bolt 17 is threaded through the closed end of the tube 14 and extends in 85 alinement with the rod 10 and forms a stop against which the inner end of this rod abuts when the spring 15 is contracted.

It will be seen that the movement of the plunger member 13, therefore, may be ad- 90 justed by adjusting the screw or bolt 17, that is the movement of this plunger member 13 may be shortened or lengthened as may be desired. It will also be seen that the spring 15 may be tensioned by the tube 14. A wire 95 18 or the like is preferably engaged with the bolt 17 and with a hook 19 on the end 6 of the cylinder 5 so as to prevent the loss of this bolt. A lug 20 is provided on the exterior of the cylinder 5 and is pivoted to the 100 crank D.

A nipple 21 is engaged in the intake manifold A and a nipple 22 extends from the cylinder 5 adjacent the end 6. A flexible hose or the like 23 is engaged with these 105 nipples 21 and 22. When the internal combustion engine is in operation, a certain amount of suction is created in the intake manifold A as is well known. This suction becomes greater as the engine speeds up. 110

In the operation of this device, it will be seen that when the accelerator F is de-

pressed, the device will be moved to bring the crank C so as to open the butterfly valve. As the engine speeds up, the suction in the intake manifold A will tend to create a vacuum in the cylinder 5 through hose 23, thereby drawing plunger 13 toward end 6 of the cylinder and compressing the spring 15. This action of the plunger will cause the closing of the butterfly valve.

10 It will therefore be apparent that by a proper adjustment of the tube 14, this device may be utilized as a governor for preventing excessive speed of the internal combustion engine.

15 It is thought that the construction, operation, and advantages of the invention will be now clearly understood by those skilled in the art without a more detailed description thereof. It is desired, however, to point 20 out numerous changes in the details of construction, and in the combination and arrangement of parts which may be resorted to without departing from the spirit of invention as hereinafter claimed, or sacrificing any 25 of its advantages.

Having thus described my invention, what I claim as new is:—

1. A device of the class described for attachment between an accelerator and the 30 operating means of a butterfly valve embodying means for shortening the device operable by suction created in the intake manifold.

2. A device of the class described includ- 35 ing a cylinder, a plunger in the cylinder, a rod attached to the plunger, means for normally holding the plunger toward one end of the cylinder, and means for communicating the cylinder with the intake manifold of an internal combustion engine.

3. A device of the class described includ- 40 ing a cylinder, a plunger in the cylinder, a

rod attached to the plunger, means for normally holding the plunger toward one end of the cylinder, means for communicating 45 the cylinder with the intake manifold of an internal combustion engine, and means for limiting the movement of said rod.

4. A device of the class described includ- 50 ing a cylinder, means for attaching the cylinder to an accelerator, a plunger slidable in the cylinder, a rod attached to the plunger, a spring in the cylinder tending to hold the plunger toward one end of the cylinder, and means for tensioning the spring and 55 means for connecting the cylinder to the intake manifold.

5. A device of the class described includ- 60 ing a cylinder, a plunger slidable in the cylinder, a spring tending to hold the plunger at one end of the cylinder, a tube threaded through the other end of the cylinder for receiving the spring and having a closed outer end, a rod extending through the plunger, fixed thereto, and terminating 65 within the cylinder, said rod adapted to be attached to the crank of a butterfly valve, a bolt extending through the closed end of the tube in alignment with the rod, thereby limiting the movement of the plunger in 70 the cylinder, said cylinder provided with a nipple adapted to be communicated with the intake manifold of an internal combustion engine, and means for attaching the cylinder to an accelerator.

6. A device of the class described for at- 75 tachment between an accelerator and the operating means of a charge regulating valve of an internal combustion engine em- bodying means for varying the length of 80 the device, said means being automatically operable during the operation of the engine.

In testimony whereof I affix my signature.
ARNOLD L. COUTY.
